UNITED STATES PATENT OFFICE.

JOHN P. THURELL, OF NORTH ADAMS, MASSACHUSETTS.

LAST.

No. 873,635.

Specification of Letters Patent.

Patented Dec. 10, 1907.

Application filed August 22, 1906. Serial No. 331,619.

To all whom it may concern:

Be it known that I, JOHN P. THURELL, a citizen of the United States, residing at North Adams, in the county of Berkshire and State 5 of Massachusetts, have invented new and useful Improvements in Lasts, of which the follow is a specification.

This invention relates to lasts of that type in which the fore-part section and heel section 10 are pivotally connected, and the object of the present improvement is to provide an effective latch attachment, as well as other details of construction which will render devices of this class more effective in their operation and practical service.

The present invention embodies improvements on the lasts disclosed by my pending applications, serially numbered 283,150 and 291,161, filed respectively October 17, 1905, 20 and December 8, 1905.

In the drawings, Figure 1 is a side elevation of a last embodying the features of the invention. Fig. 2 is a longitudinal vertical section of the same. Fig. 3 is a detail perspective view of the improved socket and guard or wear plate forming part of the last. Fig. 4 is a longitudinal section of a portion of the last showing a reversal of parts thereof.

Similar numerals of reference are employed to indicate corresponding parts in the several views.

The numerals 1 and 2 respectively designate the fore and rear sections of a last, which are pivotally connected by a transversely extending pin 3, the fore section of the last having a rear curved extension 4 fitting in a corresponding concaved seat 5 in the rear section of the last. The extension 4 has an arcuate edge 6, which is practically a segment of a true circle struck from the center of the extension where the pin 3 passes therethrough. The rear upper portion of the fore section 1, and the front upper portion of the rear section 2, above the extension 4 and 45 concaved seat 5, are cut away to permit movement of the two sections, one towards the other, and by means of the extension 4 the range of movement of the two sections is materially increased. A metallic plate 7 is 50 secured to the rear section and projects into a slot 8 of the fore section, the pin 3 extending through the said plate. The slot 8 opens out through the upper rear portion of the fore section and has a pin 9 extending transversely thereacross. In a slot 10 in the upper 55 front portion of the rear section 2, a hollow

latch 11 is pivotally mounted, the said latch preferably consisting of a piece of bent or doubled sheet metal which fits over the upper edge of the plate 7, and between the upper edge of the said plate and the top of the latch a spring 12 is interposed and inclosed by the latch, the function of the said spring being to throw the latch 11 upwardly far enough at its forward extremity to strike against the pin 9 and prevent the two last sections from having movement. This latch is very simple and positive in its operation, and when it is depressed it moves downwardly over the plate 7 without obstruction, in view of the fact that the bottom of the said latch is open. When the latch is released from contact with the pin 9 it is movable with the plate 7 into the slot 8 below the said pin 9, but the moment that the last sections are disposed in normal position the spring 12 automatically forces the latch upwardly to bring the front end thereof in engagement with the pin 9.

Another feature of improvement in the present last is the combined socket and wear plate shown applied in Fig. 2 and in detail by Fig. 3. The socket 13 is practically integral with a wear-plate 14 conforming in contour to the upper portion or top edge of the rear section 2, and when the socket is driven fully downwardly into the section 2, the plate 14 bears closely against the upper edge of said rear section and protects the latter. The socket 13 and plate 14, in view of their practical integral assemblage, may be simultaneously applied, and the use of the wear-plate will be found exceptionally advantageous in rendering the section 2 more durable.

The parts of the improved last are simple and can be readily assembled: The jack is of material advantage in operating the last, and the latch disengaging plunger being prevented from having rotation will always occupy an operative relation to the latch.

In Fig. 4 a reversal of parts of the improved last is shown and consists in pivoting the latch 11 to the fore-section and arranged to engage a pin 9 in the rear section. The curved extension 4 is also formed with the rear section and projects in a concaved seat 5 constructed in the fore-section.

Having thus described the invention, what is claimed, is:

1. A divided hinged last comprising a fore-part section and a heel section, a plate secured to one of the sections and movably ex-

- tending into the other, a pivot device extending through portions of the two sections and the plate, and a hollow latch pivotally held on the upper portion of the plate and movable downwardly over the upper edge of the latter, the latch embracing the upper edge of the plate when fully depressed, one of the last sections having a stop device which is engaged by the free end of the latch.
- 10 2. A divided hinged last comprising a fore-section and a heel section, a plate secured to the heel section and movable into the fore section, a pivot device extending through portions of the two sections and the plate, a
- 15 stop device in the upper rear portion of the fore section, a hollow latch secured to the heel section and movable over the plate and adapted to have its front extremity engage the said stop device, and a spring interposed

between the plate and latch and inclosed by 20 the latter.

3. A divided hinged last comprising a fore-part section and a heel section, a plate for pivotally coupling the two sections, a hollow latch movably connected at one extremity on 25 the upper portion of the plate, the latch when moved to clearing position embracing the upper portion of the plate, and means carried by one of the last sections for engagement with the free end of the latch.

In testimony whereof I have hereunto set my hand in presence of two subscribing witnesses.

JOHN P. THURELL.
